CLAIM

The ornamental design for instrument display screen or portion thereof with graphical user interface for preparation of bio-block, as shown and described.

DESCRIPTION

The FIGURE is a front view of instrument display screen or portion thereof with graphical user interface for preparation of bio-block, showing our new design.

The broken lines showing a display screen and elements of the graphical user interface illustrate portions of the article, and form no part of the claimed design.

1 Claim, 1 Drawing Sheet
